COVERED PITCHER

Jack E. Brown, 47 Larkspur Road,
North Stamford, Conn.

Filed Mar. 31, 1971, Ser. No. 130,056

Term of patent 3½ years

Int. Cl. D7—01

U.S. Cl. D44—21

FIG. 1 is a side elevational view of a covered pitcher showing my new design; the side opposite being a mirror image thereof;

FIG. 2 is a rear elevational view thereof;

FIG. 3 is a front elevational view thereof; and

FIG. 4 is a top plan view thereof.

The bottom is substantially plain and unornamented.

I claim:

The ornamental design for a covered pitcher, as shown and described.
